SAFETY-STEP FOR LADDERS

John T. Hennessy, New Britain, Conn.

Application June 30, 1934, Serial No. 733,228

2 Claims. (Cl. 228—17)

My invention relates to improvements in safety-steps for ladders of the form that is provided with means for cooperating with the rungs of a ladder for support and when in position is adapted to serve generally after the manner of an ordinary step for supporting a workman or fireman, as the case may be, and the object of my improvement is to produce a safety-step for ladders that is easily applied to a ladder, that is relatively light as to weight, that is relatively safe under conditions of use, that is hinged supported so as to permit of swinging out of the way and thus permit of free travel along the ladder, and that has openings when so swung out of the way to permit of access of the feet to the adjacent rung, and that, furthermore, by the use of extensions is adapted for use as a pendant platform on the underside of the ladder and in which last named use it may be used in cooperation with a mating structure of similar form.

In the accompanying drawing:—

Figure 1 is a plan view of my improved safety-step for ladders in position for use as a step as applied to a ladder.

Fig. 2 is a side elevation of the same.

Fig. 3 is a front elevation of the same.

Fig. 4 is a front elevation with the step in upward tilted position.

Fig. 5 is a side elevation of the same, in part broken away and with a foot shown diagrammatically through one of the openings.

Fig. 6 shows the hook member.

Fig. 7 shows an extension, with associated parts in broken lines.

My improved safety-step for ladders comprises a step proper 10 that, as shown, is in the form of a grid-like diminutive platform that is of ample proportions for the accommodation of the feet of the operator, a carpenter or painter or other workman or a fireman.

Means for support are provided that are adapted to cooperate with the rungs 11 of the ladder 12 so that the step 10 may be operatively supported in a substantially horizontal position for conditions of use and that, furthermore, permit of swinging the step upwardly out of the way and rest against the adjacent ladder structure. Said means for support are in the form of a hook structure 13 that is connected by one end to the step 10 and that is adapted by its upper end to hook upon one of the rungs 11 above the step.

Openings 14 in the step permit of access of the feet to the adjacent rung when the step is in the tilted position.

The step 10 in the preferred form is made of cast aluminum and thus the grid-like form or grating form of structure is provided in the form of any desired arrangement of openings 15 bordered by bar-like members 16 of sufficient size 5 and distribution to provide the needed strength. The openings 15 are virtually lightening openings and these are smaller than the foot-openings 14.

The foot-openings 14 are located adjacent to the rear edge 17 of the step 10 with the latter 10 in horizontal position though actually in slightly forward spaced relation to said edge 17, this because the step 10 is extended slightly rearward of the adjacent supporting rung 11.

The rear end portion 18 of the step 10 rests 15 upon the particular rung 11 that serves as the supporting rung, overhanging the same as mentioned and projects forwardly, the front end portion 19 thereof being supported by being hung from the lower end portion 20 of the supporting 20 hook 13.

The means for removably hingedly connecting the step with the rung and also the means for preventing the step from slipping forwardly off from the rung are provided on the bottom side of 25 the rear end portion 18. Separate parts may be applied to the step structure to obtain the results mentioned or in a cast structure they may be formed integrally.

The hinge structure, arranged one on each side, 30 is in the form of a hook-like or U-shaped hinge member 21 that has the mouth or opening 22 to admit the rung 11 at the rear.

Spaced rearward from the hinge member 21 is a dependent lug or projection 23 that serves to 35 limit the forward sliding movement of the step along the rung.

Hinge members of a different form are provided on the under side of the front end portion 19 of the step 10, being in the form of transversely directed sleeves 24, one on each side, the openings in which receive the lower end portion 20 of the hook 13.

Said hook 13 is made of relatively heavy rod material and the said lower end portion 20 is composed of the two ends thereof, bent at right-angles inwardly, with the said two ends 25 individually slipped through the openings in the hinge sleeves 24.

Above the hinge ends 25 the hook 13 comprises 50 a pair of upwardly directed side bars 26 of sufficient length to provide the reach desired and the upper ends thereof are cross-connected by means of a cross-bar 27 so as to provide a U-shape for the structure of the hook. Said cross-bar 27 is 55

spaced below the actual upper end of the structure of the hook by reason of return bend portions or hooks proper that constitute the upper end portion. Said return bends or hooks 28 are 5 adapted to hook upon the particular rung 11 selected for support and individually serve as the connecting means intermediate the side bars proper 26 and the cross-bar 27.

Thus in applying the structure to a ladder the 10 rear end portion 18 of the step 10 is placed upon a rung 11 with the portion between the hinge member 21 and the lug 22 making the supporting contact and the upper end portion 29 of the hook engaged with a rung 11 that is spaced a suitable 15 distance thereabove.

Tilting out of the way involves merely lifting the front end of the step, the structure as a whole stretching out generally flatwise with the upper end portion 29 of the hook slipping out of the way 20 through the adjacent opening or space 30 between adjacent rungs.

The extension structure for use of the step on the under side of the ladder may be in the form of a chain structure 31, one on each side, that is 25 equipped at its ends with individual hook devices for effecting connection respectively with the return bends 28 and with a rung 11. A plain hook 32 may be used at the upper end for engagement with the rung and a snaphook 34 at the lower end 30 for engagement with the bends 28.

The structure described is easily applied to a ladder of common form such as is used by firemen and painters and the like.

The openings 14 permit of access of the foot or 35 feet of the operator to the adjacent rung of the ladder when the step is in the tilted position. These openings are shown as of rectangular form. The border walls thereof may be rounded or oval

or any modification thereof. The more numerous lightening openings 15 are usually too small to admit the foot.

The hook cooperates with the step proper to make the structure as a whole safe and reliable 5 under conditions of use.

I claim as my invention:

1. A safety-step for ladders comprising a platform in the form of a one-piece gridlike structure having means at the forward end for operatively engaging with a rung of a ladder, pintle openings provided respectively adjacent the rear corners extending transversely and in alignment, a hanger in the form of a rod bent so as to provide for the middle portion a hook for making 10 supporting engagement with another upwardly spaced rung and side arms inclined towards said corners, and integral pintle ends projected from the lower ends of said arms through said openings, with the butt ends opposed one to the other, 15 whereby extension of said pintle ends will permit said butt ends to be brought into abutment and welded together, the means for engaging with the first mentioned rung serving to provide a hinge connection for permitting tilting the platform upwardly, and said platform being provided with a pair of foot-admitting openings for providing 20 supporting engagement with feet with said first mentioned rung.

2. In a safety-step for ladders, a platform and support therefor arranged to permit of a horizontal position for the platform for use as a step and for tilting the platform upwardly out of the way and with a rung of a ladder serving the axis 30 for such tilting, said platform being provided with 35 foot-openings for admitting feet to said rung with the platform in such tilted position.

JOHN T. HENNESSY.
